ELECTRIC TUBE DISPLAY

Filed Nov. 9, 1929

Inventor:
Lyman E. Klotz
By Wm. H. Klotz
Atty:

UNITED STATES PATENT OFFICE

LYMAN E. KLOTZ, OF PEORIA, ILLINOIS, ASSIGNOR TO ELECTRIC TUBE SIGNS, OF PEORIA, ILLINOIS, A COPARTNERSHIP COMPOSED OF H. E. LONG AND L. E. KLOTZ

DESIGN FOR AN ELECTRIC-TUBE DISPLAY

Application filed November 9, 1929. Serial No. 33,394. Term of patent 3½ years.

To all whom it may concern:

Be it known that I, LYMAN E. KLOTZ, a citizen of the United States, residing at Peoria, in the county of Peoria and State of Illinois, have invented a new, original and ornamental Design for Electric-Tube Displays, of which the following is a specification, reference being had to the accompanying drawing, forming part thereof.

The figure is a plan view of an electric tube display showing my new design.

I claim:

The ornamental design for an electric tube display, as shown.

LYMAN E. KLOTZ.
